UNITED STATES PATENT OFFICE.

HENRY SWALLEY, OF MILWAUKEE, WISCONSIN.

LEDGER BALANCE-SHEET.

SPECIFICATION forming part of Letters Patent No. 619,366, dated February 14, 1899.

Application filed July 12, 1897. Serial No. 644,275. (No model.)

To all whom it may concern:

Be it known that I, HENRY SWALLEY, a citizen of the United States, and a resident of Milwaukee, in the county of Milwaukee and 5 State of Wisconsin, have invented certain new and useful Improvements in Ledger Balance-Sheets; and I do hereby declare that the following is a full, clear, and exact description thereof.

10 My invention relates to balance-sheets used particularly in connection with bank-ledgers; and it consists in certain peculiarities of construction and combination of parts, as will be fully set forth hereinafter and subsequently 15 claimed.

In the drawings, Figure 1 is a plan view of the device embodying my present invention partially broken away to better illustrate certain details of construction. Fig. 2 is a longitudinal sectional view on the line 2 2 of Fig. 1. Figs. 3 and 4 are detail sectional views taken, respectively, on the lines 3 3 and 4 4 of Fig. 1 drawn to an enlarged scale.

Referring to the drawings, A represents a 25 casing or pocket adapted to be either permanently or temporarily bound into a ledger, (according as the latter is to be a permanent or loose-leaf ledger,) there being a series of these casings or pockets distributed at intervals through the book, with any suitable or desired number of regular ledger-leaves between said casings or pockets. B is a transverse strip forming a back-stop for the inner or rear edge of the movable balance-sheet C. 30 This pocket A is preferably formed of paper or cardboard, which may have suitable index-rulings on the exterior, as shown, and which may be lined on the inner surfaces with suitable thin textile fabric, if desired.

40 D D are small pieces of wood or any other suitable material forming the front and spring stops of my device and are secured just within the open front end of the said pocket A, at the top and bottom of the same, as shown.

45 E E are strips of elastic webbing or other suitable material secured to the rear part of the balance-sheet C and to the rear or inner end of the pocket A, back of the back-stop B, as shown at a a, and to guard against undue 50 thickness the balance-sheet C and back-stop B are preferably recessed, as shown at b b, so

that the said elastic strips E E may be flush with their upper surfaces, this construction greatly facilitating the movement of the sheet C in and out of the pocket A. The sheet C is 55 made of several layers of paper or cardboard, the central layer being cut out, as shown at d d, on its upper and lower edges to afford room for the movement of the springs F F. These springs are preferably formed of pieces 60 of spring-wire, doubled and bent, as shown, and with their ends e e secured in said middle layer of the sheet C, the outermost part of each spring having a central offset or shoulder g for engagement with the outer or front 65 edge of the adjacent stop D, so as to hold the strip C in the extended position, the said sheet C being itself formed with offsets or shoulders h h for engagement with the inner or rear edges of said stops D D to limit the outward 70 movement of the said sheet, and the spaces d d permitting the outermost parts of each spring F to be pushed inward, thereby freeing the spring-shoulders g from engagement with the strips D, when the elastic strips E will 75 instantly draw back the sheet C within the pocket A. The upper layer of the sheet C is preferably provided with a silicious or similar coating, so as to form a readily-erasable surface, and is further provided with horizontal lines and vertical column-rulings, these 80 columns showing when the sheet C has been pulled out from the pocket and being respectively headed to indicate the nature of the entries on the said horizontal lines, the said 85 columns (illustrated in the present drawings) being respectively marked "Overdraft," "Balance," "Account No.," and "Name." Inasmuch as the entries in the first two columns are subject to daily change these entries are 90 to be made with a lead-pencil, and to guard against the premature or accidental erasure or blurring of the said lead-pencil entries, which would be liable to occur from the frequent drawing-out and return of the sheet C 95 and consequent rubbing of the upper surface of said sheet against the inner surface of the upper part of the pocket A, the said upper layer of the said sheet C is embossed or otherwise provided with raised vertical division-lines i i between the several described columns, whereby this liability to erasure is 100

obviated, as the said inner surface of the pocket A is thus prevented from contact with the adjacent surface of the sheet C bearing the lead-pencil entries.

5 Each sheet C is provided with its appropriate index-tag j, marked with the proper index-letter, and when the sheet C has been retracted within the pocket A by the action of the elastic strips E this index-tag alone projects beyond the edge of the pocket, and preferably these tags are made integral with the sheets or, if not, they are very firmly secured thereto, so as to serve as the means of pulling the said sheets out of their pockets when it is desired to make changes or examine the entries on the sheets.

The most convenient method of using my device is to have the accounts alphabetically arranged by name, one letter to a sheet, and therefore as the balances (or overdrafts) are corrected at the close of business each day in the appropriate columns the standing of any account can be instantly determined by pulling out the sheet C having the proper index-letter, and if any change is to be made the springs F F will hold the said sheet rigid until this is done, thereby saving a great deal of time otherwise consumed in turning over the leaves of the ledger until the account in question is found. The number of elastic strips E E employed is immaterial; but with the use of two, placed, as shown, adjacent to the upper and lower edges of the sheet C, the said sheets will move in and out evenly no matter at what point the tag j is located by which the sheets are drawn out, and hence the said tags are preferably arranged in a different horizontal line on each succeeding sheet C, so that the said tags will all be exposed to view in regular order in the complete ledger. By reason of the described retraction of the balance-sheets within the pockets the ledger is made of the ordinary length, the said pockets coming flush with the regular ledger-leaves, and hence my device is more compact and convenient than it would be if the balance-sheets containing the lead-pencil entries were permanently exposed to view, besides which said entries are less liable to accidental erasure or blurring than would be possible if the sheets were permanently exposed and are never in the way when entries are to be made on the regu-

lar ledger-leaves or when the latter are examined.

Having now described my invention, what I claim as new, and desire to secure by Letters Patent, is—

1. The combination in a ledger of a series of casings or pockets, bound in or secured thereto at intervals throughout the book with any suitable or desired number of regular ledger-leaves interposed between said casings or pockets, the latter being flush at their front edges with the regular ledger-leaves, and a series of movable balance-sheets adapted to be partially withdrawn from or restored to place within said casings or pockets, and stops for preventing the complete separation of said casings or pockets and said balance-sheets.

2. The combination in a ledger, of a series of casings or pockets bound in or secured thereto at intervals throughout the book with their front edges flush with those of the regular ledger-leaves, a series of properly-ruled balance-sheets, series of horizontally-arranged elastic strips connecting the inner edges of said balance-sheets to the inner rear parts of said casings or pockets and index-tags projecting from said balance-sheets, whereby each balance-sheet may be withdrawn by means of its tag from its casing or pocket and be automatically retracted within the same by the action of said elastic strips.

3. The combination with a casing or pocket adapted to be bound into a ledger, of a transverse back-stop within said pocket, front stops secured within the open front end of said pocket at top and bottom, a movable balance-sheet having shouldered edges for engagement with the rear edges of said front stops, spring-stops on said sheet for engagement with the front edges of said front stops, and elastic strips connecting the rear part of said balance-sheet with the rear part of said pocket within the latter, substantially as set forth.

In testimony that I claim the foregoing I have hereunto set my hand, at Milwaukee, in the county of Milwaukee and State of Wisconsin, in the presence of two witnesses.

HENRY SWALLEY.
